CLAIM

The ornamental design for a glove, as shown and described.

DESCRIPTION

FIG. 1 is a front elevation view of a glove showing our new design;

FIG. 2 is a top plan view thereof;

FIG. 3 is a bottom plan view thereof;

FIG. 4 is a rear elevation view thereof;

FIG. 5 is a left side elevation view thereof;

FIG. 6 is a right side elevation view thereof; and,

FIG. 7 is a perspective view thereof.

The Figures referred to above show a left-hand glove. A right-hand glove is a mirror image thereof.

The broken lines show portions of the glove and form no part of the claimed design.
